UNITED STATES PATENT OFFICE.

HENRY G. GOSELIN AND WILLIAM B. MAHERN, OF BERLIN, NEW HAMPSHIRE.

HIGH-PRESSURE FLUID-PUMP.

1,356,063.

Specification of Letters Patent. Patented Oct. 19, 1920.

Application filed April 28, 1920. Serial No. 377,307.

To all whom it may concern:

Be it known that we, HENRY G. GOSELIN and WILLIAM B. MAHERN, citizens of the United States, residing at Berlin, in the 5 county of Coos and State of New Hampshire, have invented a new and Improved High-Pressure Fluid-Pump, of which the following is a specification.

Our invention has reference to multiple 10 impeller pumps of that type that includes in their structural arrangement a plurality of impellers coöperative with a common suction, an inclosing casing into which is received the simultaneous discharge from 15 the several impellers, combined with means for creating increased efficiency of the discharge from the said impellers, and our said invention primarily has for its purpose to provide an improved construction of pump 20 of the general character stated that embodies the advantages of an economical, compact and simple coöperating arrangement of parts which are so designed whereby to provide a pump of high efficiency and pressure. 25

With other objects in view that will hereinafter be stated, our invention consists in the multiple impeller pump consisting of the peculiar construction and novel arrangement of the parts set forth in the following detailed description, specifically stated in the appended claims and illustrated in the accompanying drawings, in which:

35 Figure 1 is a side elevation of a high pressure fluid pump in which is embodied our invention.

Fig. 2 is a vertical central longitudinal section thereof taken on the line 2—2 on 40 Fig. 3 and illustrates a preferred arrangement of the revolving impellers or vanes and the stationary impellers or vanes.

Fig. 3 is a top plan view of the pump structure shown in Figs. 1 and 2.

45 Fig. 4 is a transverse section of our pump taken substantially on the line 4—4 on Fig. 2.

Fig. 5 is a section taken substantially on the line 5—5 on Fig. 2.

50 Fig. 6 is a detail vertical section of the modified form of our invention in which is embodied a single inner revolving impeller and an outer stationary impeller that encircles the inner impeller as hereinafter 55 more definitely stated.

Fig. 7 is a diagrammatic side elevation

of the inner and outer impellers shown in Fig. 6.

Fig. 8 is a diagrammatic view that illustrates the relative shape and coöperating 60 positions of the blades of the two impellers shown in Figs. 6 and 7.

In the practical development of our invention and in the preferred arrangement thereof, as illustrated in Figs. 1 to 4, inclusive, a shaft 1 is revolvably mounted in a pair of upright bearings 2—2 mounted on sub-bases 3, the base portions at each end being secured upon a main base 4, in any suitable manner, and at a point midway 70 each set of bearings 2—2, the shaft section 1 that is mounted therein, is provided with fast and loose pulleys 5—50, as shown.

At a point, preferably midway the sub-bases 3—3, is mounted the pump mechanism proper, the construction of which is best shown in Figs. 2, 3 and 4, by reference to which it will be seen that a pair of impellers 6 are keyed or otherwise fastened to and are oppositely disposed on the said 80 shaft and the said oppositely disposed impellers 6—6 are located, one at each side of a centrally disposed stationary impeller 9 with which the revolvable impellers coöperate and from which the drawn and impelled fluid passes into the pump discharge, which latter in our construction of pump is in the nature of an annular chamber or shell 7 provided, at one side, with an outlet 8, as is best shown in Fig. 4. 90

The shell 7 is formed with a central restricted annular passage 70 that is in communication with the peripheral edge of the inner or stationary impeller 9 and it also includes lateral portions 71, each provided 95 with an annular flange 72, the purpose of which will presently appear.

By referring more particularly to Figs. 1 and 4, it will be observed that our pump structure includes what is hereinafter termed 100 a suction shell, one of such shells being located at the outside of each of the oppositely disposed revolving impellers and each of the said suction shells is of conical shape with its base portion provided with an annular flange 11 for bolting onto the flanges 72 at their respective sides of the annular shell or casing 7, the latter inclosing the peripheral edges of the several impellers, as is clearly shown in Fig. 1. 105

Each suction shell includes an internal or base member 12 and the latter is also of 110

conical form but it is so angled with respect to the outer conical portion of the said vacuum shell that a restricted annular discharge 13 is provided that communicates 5 with the annular rim of impelling blades 14 that are secured to the impeller body 6, it being understood that the discharge end 13 of the left hand suction shell communicates with the adjacent left hand impeller 10 6 and the discharge 13 of the other or right hand suction shell communicates with its adjacent impeller 6.

15 designates the main suction pipe or inlet and it connects with a U-shaped suction head 16, the opposite ends 16^a—16^b of which have clamp rims for attaching thereto the suction pipes 17—17, which latter communicate with the suction shell, at their respective ends of the pump, as is best shown 20 in Fig. 3.

Each of the revoluble impellers, at the peripheral edge thereof, carries a series of radially projected steel blades or vanes 14 and these extend across their respective peripheral impeller body edges at an angle of approximately forty-five degrees and the 25 said blades of the oppositely disposed impellers are so positioned relatively to their respective body members so as to deliver the incoming fluid at high speed through a series of intake passages of comparatively small area and against a series of stationary vanes in the nature of steel blades 20 that are attached to and radially projected 30 from the inner or stationary member 9.

To further increase the force of the fluid passing through the numerous intake passages, as stated and shown, the stationary blades are so shaped that while adapted for 40 receiving the full force of the fluid impact thereagainst they also serve to direct the fluid as it discharges into the annular passage to the discharging compartment or shell that connects with the pump outlet.

45 The stationary impelling blades in face view are V-shaped, the section at one side being disposed at an angle to the peripheral face of the central impeller body and diametrically opposite to the line of angle of 50 the blades of the revoluble impeller at the adjacent side of the said stationary impeller, the other sections of the said V-shaped blades being likewise angled with respect to the coincident blades on the revoluble impeller 55 at their adjacent side of the stationary impeller.

21—21 designate brace or stay members for rigidly holding the inner and outer conical portions of the suction shells together, 60 and the outer end of each suction shell terminates in a flattened head 75 in which is mounted a stuffing box and gland 22—23 for the shaft that carries the revoluble impellers. The inner end of each of the conical 65 members has an aperture 77 through which

the pump shaft sections freely pass, as shown.

From the foregoing taken in connection with the drawings, the complete construction, the manner of operation and the advantages of our invention will be readily apparent to those skilled in the practical use and handling of pumps of the character mentioned.

The water that is drawn into the inlet is 75 divided and passes into the two oppositely disposed suction shells and when entering each of said suction shells the water is centrifugally directed to the annular discharges 13 through which the water passes laterally 80 with respect to the rotation of the oppositely disposed revoluble impellers and strikes the blades 14. The outside impellers 6—6 travel in the direction of the arrows a—a. The fluid that passes toward the impeller blades 85 20 engages the inwardly inclined faces of the said blades in such manner that outgoing fluid is directed under great speed and pressure into the annular shell or chamber 7 from which the fluid passes through the 90 pump outlet, it being understood the peculiar construction and coöperative arrangement of the revolving impellers and the stationary impeller blades is such that the intake capacity of the pump is materially multiplied and a high speed and pressure pump 95 of great efficiency is provided whose motive power is greatly increased by reason of the manner in which the indrawn fluid is caused to engage with and pass through the impeller vanes or blades, to a common passage 100 that leads to the pump outlet.

In Figs. 5 to 9 is illustrated a somewhat modified form of our invention. In this latter form, a centrally disposed impeller 30 is 105 mounted to turn with a shaft 35 and the blades on the said impeller are shaped and peripherally mounted on the impeller body the same as in the central and stationary impeller shown in our other form described, 110 it being understood, by referring to Fig. 6, that the indrawn fluid, as it passes through the annular passage of the suction shells, engages the vanes or blades of the revoluble impellers and causes such impellers to revolve with the shaft in the direction of the arrows b—b and pocket the fluid that enters 115 from the opposite sides and directs it, under considerable impact, against and through the passages between the fixedly held outside 120 impellers (see arrows c—c on Fig. 5) and into the annular chamber that receives the discharge fluid and from which the said fluid passes to the pump outlet.

In the modified form, as also in the preferred form before described, the inner conical portion of the suction shells prevent the water drawn into the said shells from rubbing against the center of the impellers and thereby prevents friction and consequent 130

loss of power particularly when the impellers are arranged as in the preferred form shown in Figs. 1 to 4.

What we claim is:

5 1. In a centrifugal pump the combination with an impeller mounted on a shaft and revoluble therewith, the said impeller having radial blades angularly disposed with respect to the peripheral edge of the impeller, a casing surrounding the impeller and including an annular passage having an outlet, the said passage being in communication with the rim of the impeller, an annular rim of deflector blades interposed 10 between the impeller rim and the said annular passage, the blades of which are disposed at an angle opposing the angle of the impeller blades, and a fluid intake in communication with and through which the 15 fluid is directed to the bladed periphery of the impeller.

2. In a centrifugal pump the combination with an impeller mounted on a shaft and revoluble therewith, the said impeller having radial blades angularly disposed with respect to the peripheral edge of the impeller, a casing surrounding the impeller and including an annular passage having an outlet, the said passage being in communication with the rim of the impeller, an annular rim of deflector blades interposed 20 between the impeller rim and the said annular passage, the blades of which are disposed at an angle opposing the angle of the impeller blades, and a fluid intake in communication with and through which the 25 fluid is directed to the bladed periphery of the impeller, the said intake including a suction shell having an annular peripheral discharge and means for directing the in-drawn fluid toward the said annular peripheral discharge, the latter being in communication with the bladed periphery of the impeller and adapted for directing the fluid 30 laterally across the said bladed rim.

3. In a centrifugal pump, the combination with a stationary impeller having angularly disposed radially projected blades, a shaft, other impellers revoluble with the 35 shaft, one of the said other impellers being located at each side of the stationary impeller, each of the said revoluble impellers having radially projected blades, a casing having an annular fluid passage in communication with the stationary impeller rim and having a single discharge outlet, a suction shell located, one at the outer side of each of the revoluble impellers, a fluid inlet to each suction chamber, means within each 40 suction shell for directing the incoming fluid to discharge laterally against the blades of their adjacent revoluble impellers, the blades of the revoluble and the stationary impellers being relatively so disposed 45 whereby fluid entering from opposite sides

is deflected under impelled force into the aforesaid annular fluid passage.

4. In a centrifugal pump, a pair of oppositely facing revoluble impellers mounted on and movable with a shaft, a stationary 50 impeller located between the revoluble impellers, the peripheries of all of the impellers having radially extended blades, the said blades being angularly disposed with respect to the peripheral faces of their respective impeller bodies, the blades of the revoluble impellers being angled in opposite directions to each other, and the blades of the stationary impeller being angled in reverse direction to the blades at the adjacent abutting faces of the revoluble impellers, a casing that surrounds the several impellers and has an annular water chamber that extends around and in communication 55 with the bladed rim of the stationary impeller, the said annular water chamber having an outlet, a suction chamber for each revoluble impeller, an intake for each suction chamber and means within each suction chamber for directing the in-drawn water 60 to discharge laterally across the bladed rims of their respective revoluble impellers.

5. In a centrifugal pump, a shaft, a pair of impellers mounted on the said shaft and revoluble therewith, a stationary impeller 65 located between the revoluble impellers and in close relation therewith, a casing having an annular fluid passage in communication with the rim of the stationary impeller, a suction chamber outside of each of the said 70 revoluble impellers, each of the said suction chambers having a fluid inlet and an angularly disposed outlet for discharging the fluid laterally across the rims of their adjacent revoluble impellers, the said revoluble and stationary impellers having radially and angularly disposed blades arranged 75 for impelling the incoming fluid against the blades of the stationary impeller, the blades of the latter being arranged for directing 80 the fluid laterally across the said bladed rim.

6. In a centrifugal pump, a shaft, a pair of impellers mounted on the said shaft and revoluble therewith, a stationary impeller located between the revoluble impellers and in close relation therewith, a casing having an annular fluid passage in communication 85 with the rim of the stationary impeller, a suction chamber outside of each of the said revoluble impellers, each of the said suction chambers having a fluid inlet and an angularly disposed outlet for discharging the fluid laterally across the rims of their adjacent revoluble impellers, the said revoluble and stationary impellers having radially and angularly disposed blades arranged for 90 impelling the incoming fluid against the blades of the stationary impeller, the blades 95 of the latter being arranged for directing 100 the fluid into the annular fluid passage in the casing, the latter having a discharging outlet.

of the latter being arranged for directing the fluid into the annular fluid passage in the casing, the latter having a discharging outlet, a single inlet in communication with 5 the inlets to the two suction chambers, the latter each having means for directing the indrawn fluid toward and through their annular passages in communication with their respective impeller rims.

10 7. In a centrifugal pump, a shaft, a pair of impellers mounted on the said shaft and revoluble therewith, a stationary impeller located between the revoluble impellers and in close relation therewith, a casing having 15 an annular fluid passage in communication with the rim of the stationary impeller, a suction chamber outside of each of the said revoluble impellers, each of the said suction chambers having a fluid inlet and an 20 annularly disposed outlet for discharging the fluid laterally across the rims of their adjacent revoluble impellers, the said revoluble and stationary impellers having radially and angularly disposed blades arranged 25 for impelling the incoming fluid against the blades of the stationary impeller, the blades of the latter being arranged for directing the fluid into the annular fluid passage in the casing, the latter having a discharging 30 outlet, each of the suction chambers comprising an outer fixed conical shell and an inner fixed conical body that covers the adjacent face of its coöperating revoluble impeller, the peripheral edges of the inner

and outer conical members of the suction 35 chambers being separate to provide an annular water passage for directing the fluid discharge from the suction chamber laterally through the bladed rims of their respective coöperating revoluble impeller. 40

8. In a centrifugal pump, a shaft, a pair of impellers mounted on the said shaft and revoluble therewith, a stationary impeller located between the revoluble impellers and in close relation therewith, a casing having 45 an annular fluid passage in communication with the rim of the stationary impeller, a suction chamber outside of each of the said revoluble impellers, each of the said suction chambers having a fluid inlet and an annularly disposed outlet for discharging the fluid laterally across the rims of their adjacent revoluble impellers, the said revoluble and stationary impellers having radially and angularly disposed blades arranged for 50 impelling the incoming fluid against the blades of the stationary impeller, the blades of the latter being arranged for directing the fluid into the annular fluid passage in the casing, the latter having a discharging 55 outlet, the blades of the stationary impeller being V-shaped and the blades of the opposite revoluble impellers being angled in a direction opposite to their respective adjacent portions of the V-shaped blades on the 60 stationary impellers.

HENRY G. GOSELIN.
WILLIAM B. MAHERN.
